UNITED STATES PATENT OFFICE.

WILLIS S. RICHARDSON, OF NEWARK, NEW JERSEY.

DESIGN FOR A WATCH-CROWN.

SPECIFICATION forming part of Design No. 25,696, dated June 30, 1896.

Application filed March 18, 1896. Serial No. 583,819. Term of patent 7 years.

To all whom it may concern:

Be it known that I, WILLIS S. RICHARDSON, a citizen of the United States, residing at Newark, in the county of Essex and State of New Jersey, have invented and produced a new and original Design for Watch-Crowns, of which the following is a specification, reference being had to the accompanying drawings.

10 Figure 1 is a top plan view of a watch-crown having my design applied thereto. Fig. 2 is a side view thereof.

15 The leading feature of my design consists in the raised and widely-separated ribs radiating from the center of the top of the crown to the lower or bottom edge thereof, thus exhibiting or showing a portion of the metal of the crown proper between the ribs,

in contradistinction to the old or usual style of crown, the surface of which is ornamented by forming V-shaped grooves therein.

20 A represents the central field or portion of the top of the crown, from which radiate the ribs or raised portions B, extending from said center A to the bottom or lower edge of said 25 crown, these ribs B being widely separated, as shown, thus presenting to the eye the appearance of a crown inclosed within and surrounded by a number of external ribs.

What I claim is—

30 The design for a watch-crown as herein shown and described.

WILLIS S. RICHARDSON.
